UNITED STATES PATENT OFFICE

169,566

SOUND TRANSLATING MACHINE

Richard M. Somers, West Orange, N. J., assignor
to Thomas A. Edison, Incorporated, West
Orange, N. J., a corporation of New Jersey

Application December 8, 1952, Serial No. 22,603

Term of patent 14 years

(Cl. D26—14)

To all whom it may concern:

Be it known that I, Richard M. Somers, a citizen of the United States, residing in the town of West Orange, county of Essex, and State of New Jersey, have invented a new, original, and ornamental Design for a Sound Translating Machine, of which the following is a specification, reference being had to the accompanying drawing, forming a part thereof.

Figure 1 is a perspective view from a front corner showing the front, top and righthand side of a sound translating machine, showing my new design;

Figure 2 is a lefthand side elevational view thereof; and

Figure 3 is a rear elevational view thereof.

I claim:

The ornamental design for a sound translating machine, substantially as shown.

RICHARD M. SOMERS.
